UNITED STATES PATENT OFFICE

ERNEST J. SCHUDA, OF ERIE, PENNSYLVANIA, ASSIGNOR TO LOVELL MANUFACTURING COMPANY, OF ERIE, PENNSYLVANIA, A CORPORATION OF PENNSYLVANIA

WRINGER

Application filed May 17, 1929. Serial No. 363,728.

The present invention is designed to improve wringers, particularly adapting wringers of the later types with driving gears, the driving gears being preferably arranged at the outside of the stiles. Where such gears are provided, particularly with wringers in which the means are supplied for readily removing the top roll in connection with a detachable top roll it is desirable that the gear may not interfere with the convenient removal of the top roll. It is also desirable to provide the gears with suitable housings and where the gear is to be removed it is desirable to supply the housing with a removable top so as not to interfere with the removal of the gear. These features and others are included in the invention. Other features will appear from the specification and claims.

A preferred embodiment of the invention is illustrated in the accompanying drawings as follows:—

Fig. 1 shows a front elevation of the wringer, partly in section.

Fig. 2 an enlarged sectional view of one end of the wringer.

Fig. 3 a section on the line 3—3 in Fig. 2.

Fig. 4 a section on the line 4—4 in Fig. 3.

Fig. 5 a section on the line 5—5 in Fig. 4.

Fig. 6 a section on the line 6—6 in Fig. 2.

Fig. 7 is a perspective view of a latch locking the top bar to the frame.

1 marks the wringer base, 2 and 2a the stiles, 3 the top roll, 4 the bottom roll, and 5 and 6 the shafts for the top and bottom roll respectively. The side stiles are of sheet metal, box form, and the shafts 5 and 6 extend through a slot 7 which extends through the top of the stiles so as to permit of the easy removal of the shafts. The shafts also extend through the outer wall of one of the stiles and this outer wall is provided with a slot 8 to permit such extension of the shafts, the slot 8 like the slot 7 extending through the top of the stiles.

The lower shaft operates in bearings 9 arranged in the side stile and sliding bearing blocks 10 are provided for the upper shaft also arranged in the stile and removable through the top of the stile. A spring

11 extends across the wringer, the ends of the spring resting on the sliding blocks 10. A release device is provided with a rotating sleeve 12, and locking shoulders 13, the sleeve extending through an opening 14 in a fitting 14a carried by a top bar 1a. The fitting is also supplied with vertical slots 15 through which the shoulder 13 may pass when the shoulder is turned into register. A handle 16 is arranged on the sleeve by means of which it may be turned. An adjusting screw 17 extends through the sleeve and is secured to the spring 11. This releasing device is one of common construction and is generally described in the patent to Misner #15,865 (reissue).

A bail 18 is hung on a pin 18a extending across the top bar and extends around a sliding block 10 and the end of the shaft 5, one of these mechanisms being arranged at each end of the cross bar. A latch 19 is also pivotally secured on the pin 18a and has fingers 20 which extend through slots 21 in the inner wall of the side stile. This latch has a cross plate 22 which is engaged by the spring 11 when released by the releasing device and when so engaged by the spring the latch is thrown out of engagement with the upper wall of the slot 21 releasing the top bar so that upon the operation of the safety release a secondary release of the top bar is effected permitting the detachment of the top bar and if the top bar is lifted the lifting of the top roll through the connection of the bail 18 entirely from the wringer. This is a desirable feature in that if an operator gets his hand caught the complete removal of the top roll is desirable so as to prevent injury to the hand. This is particularly true in that it disengages the gear 23 and thus stops the rotation of the top roll.

Gears 23 and 24 are fixed on the ends of the shafts 5 and 6 and are in mesh, as shown the lower shaft being the driving shaft and communicating the movement to the upper shaft.

These gears are arranged in a housing. The housing is formed with a back plate 25, this back plate being slotted to permit the insertion of the shafts and has lips 26.

extending through the slot 8 in the stile, these lips 26 being bent outwardly and engaging the inner face of the outer wall of the stile, thus locking the housing on the outer wall of the stile. This manner of forming the lips permits of their insertion into the slot in the stile from the top so that the housing may be merely slipped into place, and thus assembled. The back plate 10 also has lips 28 struck up on its rear face. These engage the front and rear faces of the stile and make more secure the connection between the back plate and the stile. A cover plate 29 is box formed and fits at 15 its open edges the edges of the back plate. Ears 30 are bent from the edges of the cover plate over the rear of the back plate and are spot welded in this position thus completing the assembly.

20 It will be noted that the top of the housing, so far described, is open and is considerably below the top of the stile. In order that the gear may be readily removed it is desirable that any cover that may be 25 provided for the housing may be removable with the top bar. In the present construction a cover 31 has a lip 32 forming a telescopic connection with the upper edge of the housing. The cover has an upwardly 30 extending projection 33 which extends into the end flange of the top bar and is spot welded on the top bar so that it is carried by the top bar into and out of place. This upward projection 33 is provided with an 35 inwardly struck-up shoulder 34 which engages the edges of the slot 8. The top bar is flange formed and seats over the top of the stiles, thus preventing the spreading of the stile and the shoulder 34 arranged in 40 the slot prevents the in-bending of the top of the stile. It will be understood that the slotting of both the inner and outer walls of the stile in order to accommodate the shafts 5 and 6 weakens very considerably 45 this stile so that this manner of bracing it against collapse, or expansion is of importance.

In the operation of the device, when the release device is operated, the spring first 50 releases the pressure, then engaging the latch releases the top bar, and the operator ordinarily grasps the top bar with the hand effecting the release, catches the top bar, and removes the wringer roll from the machine. 55 This permits the operator to simply remove, not withdraw, the engaged hand.

What I claim as new is:—

1. In a wringer, the combination of side stiles; rolls mounted in the side stiles; a 60 cross bar on the side stiles; a pressure device between the rolls and the cross bar; detachable connections between the cross bar and the side stiles; a safety release device on the cross bar releasing the pressure device; shafts for the rolls, said shafts ex-

tending through one of the stiles; and gears on said shafts outside of the stiles, said gears being normally in mesh, the side stile at the gear end of the shaft being slotted through its inner wall and outer wall 70 through its top and the side stile opposite the gear being slotted through its inner wall and to the top permitting the direct removal of the upper shaft with its gear through said slots. 75

2. In a wringer, the combination of side stiles; rolls mounted in the side stiles; a cross bar on the side stiles; a pressure device between the rolls and the cross bar; detachable connections between the cross bar and the side stiles; a safety release device on the cross bar releasing the pressure device; shafts for the rolls, said shafts extending through one of the stiles; gears on 80 said shafts outside of the stiles, said gears being normally in mesh, the side stile at the gear end of the shaft being slotted through its inner wall and outer wall through its top and the side stile opposite the gear being slotted through its inner wall 85 and to the top permitting the direct removal of the upper shaft with its gear through said slots; and straps connecting the cross bar with the upper roll. 90

3. In a wringer, the combination of side stiles; rolls mounted in the side stiles; a cross bar on the side stiles; a pressure device between the rolls and the cross bar; detachable connections between the cross bar and the side stiles; a safety release device on the cross bar releasing the pressure device; shafts for the rolls, said shafts extending through one of the stiles; gears on 100 said shafts outside of the stiles, said gears being normally in mesh, the side stile at the gear end of the shaft being slotted through its inner wall and outer wall through its top and the side stile opposite the gear being slotted through its inner wall 105 and to the top permitting the direct removal of the upper shaft with its gear through said slots; and means actuated through the action of the safety release for automatically disconnecting the detachable connections. 110

4. In a wringer, the combination of side stiles; rolls mounted in the side stiles; a cross bar on the side stiles; a pressure device between the rolls and the cross bar; detachable connections between the cross bar and the side stiles; a safety release device on the cross bar releasing the pressure device; shafts for the rolls, said shafts extending through one of the stiles; gears on 120 said shafts outside of the stiles, said gears being normally in mesh, the side stile at the gear end of the shaft being slotted through its inner wall and outer wall through its top and the side stile opposite the gear being slotted through its inner wall 125 and to the top permitting the direct removal 130

of the upper shaft with its gear through said slots; straps connecting the cross bar with the upper roll; and means actuated through the action of the safety release for automatically disconnecting the detachable connections.

5. In a wringer, the combination of side stiles; rolls mounted in the side stiles; a cross bar on the side stiles; a pressure device between the rolls and the cross bar; detachable connections between the cross bar and the side stiles; a safety release device on the cross bar releasing the pressure device; shafts for the rolls, said shafts extending through one of the stiles; gears on said shafts outside of the stiles, said gears being normally in mesh, the side stile at the gear end of the shaft being slotted through its inner wall and outer wall through its top and the side stile opposite the gear being slotted through its inner wall and to the top permitting the direct removal of the upper shaft with its gear through said slots; a housing for the gears arranged outside the stile; and a cover for the housing carried by the cross bar.

6. In a wringer, the combination of side stiles; rolls mounted in the side stiles; a cross bar on the side stiles; a pressure device between the rolls and the cross bar; detachable connections between the cross bar and the side stiles; a safety release device on the cross bar releasing the pressure device; shafts for the rolls, said shafts extending through one of the stiles; gears on said shafts outside of the stiles, said gears being normally in mesh, the side stile at the gear end of the shaft being slotted through its inner wall and outer wall through its top and the side stile opposite the gear being slotted through its inner wall and to the top permitting the direct removal of the upper shaft with its gear through said slots; straps connecting the cross bar with the upper roll; a housing for the gears arranged outside the stile; and a cover for the housing carried by the cross bar.

7. In a wringer, the combination of side stiles; rolls mounted in the side stiles; a cross bar on the side stiles; a pressure device between the rolls and the cross bar; detachable connections between the cross bar and the side stiles; a safety release device on the cross bar releasing the pressure device; shafts for the rolls, said shafts extending through one of the stiles; gears on said shafts outside of the stiles, said gears being normally in mesh, the side stile at the gear end of the shaft being slotted through its inner wall and outer wall through its top and the side stile opposite the gear being slotted through its inner wall and to the top permitting the direct removal of the upper shaft with its gear through said slots; means actuated through the action of the

safety release for automatically disconnecting the detachable connection; a housing for the gears arranged outside the stile; and a cover for the housing carried by the cross bar.

8. In a wringer, the combination of side stiles; rolls mounted in the side stiles; a cross bar on the side stiles; a pressure device between the rolls and the cross bar; detachable connections between the cross bar and the side stiles; a safety release device on the cross bar releasing the pressure device; shafts for the rolls, said shafts extending through one of the stiles; gears on said shafts outside of the stiles, said gears being normally in mesh, the side stile at the gear end of the shaft being slotted through its inner wall and outer wall through its top and the side stile opposite the gear being slotted through its inner wall and to the top permitting the direct removal of the upper shaft with its gear through said slots; straps connecting the cross bar with the upper roll; means actuated through the action of the safety release for automatically disconnecting the detachable connections; a housing for the gears arranged outside the stile; and a cover for the housing carried by the cross bar.

9. In a wringer, the combination of side stiles; rolls mounted in the side stiles; shafts for the rolls extending through one side stile; gears on said shaft outside of one of the stiles; a housing for the gear arranged on the outside of the stiles, the upper end of the housing being below the top of the stile; a cover for the housing; and a cross bar across the top connecting the stiles on which the cover is mounted.

10. In a wringer, the combination of side stiles; rolls; shafts for the rolls extending through one of the stiles, the side stile through which the shafts extend being of box form and having its outer and inner walls slotted through the top of the stile; and a cross bar of channel form having its side walls engaging the outer faces of said slotted stile and being provided with an internal shoulder engaging the edges of one of the slots in the stile to prevent the collapse of the stile.

11. In a wringer, the combination of side stiles; rolls; shafts for the rolls extending through one of the stiles, the side stile through which the shafts extend being of box form and having its outer and inner walls slotted through the top of the stile; a cross bar of channel form having its side walls engaging the outer faces of said slotted stile and being provided with an internal shoulder engaging the edges of one of the slots in the stile to prevent the collapse of the stile; gears on the shafts; a housing for the gears secured to the stile; a cover for the

housing; and a connection between the cover and the cross bar.

12. In a wringer, the combination of side stiles of box form; rolls in the side stiles; shafts extending through one of said side stiles, said stile being slotted to the top of the stile through both its inner and outer walls; gears on the shafts at the outside of the stile; a housing for the gears, said housing comprising a back plate; and lips extending from the back plate through the slot in the outer wall of the stile, said lips engaging the inner face of said outer wall and being insertable from the top of the housing.

13. In a wringer, the combination of side stiles of box form; rolls in the side stiles; shafts extending through one of said side stiles, said stile being slotted to the top of the stile through both its inner and outer walls; gears on the shafts at the outside of the stiles; a housing for the gears, said housing comprising a back plate; lips extending from the back plate through the slot in the outer wall of the stile, said lips engaging the inner face of said outer wall and being insertable from the top of the housing; and a housing plate secured to the back plate of box shape.

14. In a wringer, the combination of side stiles of box form; rolls in the side stiles; shafts extending through one of said side stiles, said stile being slotted to the top of the stile through both its inner and outer walls; gears on the shafts at the outside of the stiles; a housing for the gears, said housing comprising a back plate; lips extending from the back plate through the slot in the outer wall of the stile, said lips engaging the inner face of said outer wall and being insertable from the top of the housing; a housing plate secured to the back plate of box shape; and a cover telescoping the housing plate.

15. In a wringer, the combination of side stiles of box form; rolls in the side stiles; shafts extending through one of said side stiles, said stile being slotted to the top of the stile through both its inner and outer walls; gears on the shafts at the outside of the stiles; a housing for the gears, said housing comprising a back plate; lips extending from the back plate through the slot in the outer wall of the stile, said lips engaging the inner face of said outer wall and being insertable from the top of the housing; a housing plate secured to the back plate of box shape; a cover telescoping the housing plate; and a top bar between the stiles on which the cover is mounted.

60 In testimony whereof I have hereunto set my hand.

ERNEST J. SCHUDA.
